WASHING MACHINE

Richard S. Gaugler, Dayton, Ohio, assignor to
 General Motors Corporation, Dayton, Ohio, a
 corporation of Delaware

Application August 21, 1948, Serial No. 45,476

5 Claims. (Cl. 68—21)

1

This invention relates to domestic appliance, and more particularly to a washing machine and method of washing clothes or the like.

An object of this invention is to provide a washing machine with improved means for wringing the clothes.

Another object of this invention is to provide an improved means for wringing clothes or the like.

Further objects and advantages of the present invention will be apparent from the following description, reference being had to the accompanying drawings, wherein a preferred form of the present invention is clearly shown.

In the drawings:

Fig. 1 is a vertical cross-sectional view, partly diagrammatic, of a washing machine embodying features of my invention;

Fig. 2 is a diagrammatic representation of the controls of the washing machine;

Fig. 3 is a vertical cross-section of a modified form, during the washing operation;

Fig. 4 is a view of the machine shown in Fig. 3, during the wringing operation; and

Fig. 5 is a diagram of the controls for the machine shown in Figs. 3 and 4.

A washing machine shown in Fig. 1, and embodying features of my invention, may include a tub 10, provided with an agitator 11, driven through the medium of shaft 12 and transmission 13 from motor 14.

The agitator 11 may be of any type desired, and is here indicated as vertically reciprocable, being provided with a perforated soap chamber 15, having a removable cover 16. A flexible bellows 17, of rubber, rubber-like material, or metal, may be interposed between the agitator and tub, to provide a water seal at this point.

The transmission 13 may be any suitable transmission to impart the desired movement to the agitator 11. It may be provided with a solenoid control 18, which when energized drives (or stops, as desired) the agitator 11. The solenoid 18 may impart its control through the medium of a lever 18a or similar device.

The motor 14 may also drive the water and vacuum pump 19 through the medium of a transmission 20, indicated diagrammatically by a dotted line, which is controlled by a solenoid 21. Proper energization (or deenergization, as desired) of solenoid 21 causes motor 14 to drive or stop the pump 19. The pump 19 has its intake

2

connected to the tub 10 and by the pipe 19a and has its discharge connected to a pipe or hose 19b which may discharge into a stationary tub or drain. Some portion of hose 19b is maintained above the level of the water in tub 10 as indicated by the dotted line at 19c to prevent undesired drainage.

A water supply pipe 22 may be provided with a combined solenoid, thermostatic and constant flow control valve structure 23, which is supplied by hot and cold water pipes 24 and 25. The construction of valve structure 23 is such that it supplies water of the desired temperature to the tub 10 at a constant rate of flow.

15 The motor 14 and solenoid controls 18, 21 and 23 may be controlled by a timer, for example as indicated in Fig. 2. The timer may include a timer motor 26 which drives the timer shaft 27 through the medium of speed reduction gearing or transmission 28. The shaft 27 may have a setting knob 29 and a plurality of disc cams 30 to 34 inclusive, which respectively actuate the switches 35 to 39 inclusive. These switches establish circuits from the power lines L and L₁ respectively through the motor 14, solenoid controls 18, 21, 23 and timer motor 26.

While the foregoing washing machine structure has been described in some detail, it is to be understood that such structure may be varied, as desired.

30 Means are provided for removing the excess water, imparting a squeezing pressure on the clothes, imparting a vacuum around the clothes, and causing a flow of air through them. This produces a very efficient wringing or drying action on the clothes.

To this end a porous, flexible membrane or diaphragm 40 is placed on the washing machine in such position as to impart a physical pressure upon the clothes to squeeze them when a vacuum is imparted within the machine. For example, a cover 41 may be hinged at 42 to the tub 10. It may be provided with openings 43. The membrane 40 may have its periphery 44 secured to the periphery 45 of the cover 41. The periphery 46 of the tub 10 is outwardly flared, or otherwise shaped, to receive the periphery 44 of the membrane 40. A sealing or wedging action is thus produced when a vacuum is imparted within the tub 10. A handle 48 is provided on the cover 41 to lift the same when the vacuum is broken.

Preferably the membrane 40 is of such porosity that at pressure differences less than one-half atmosphere the membrane will act as a water-tight and substantially air-tight membrane, particularly when wet, as it will be following a washing action. When a further vacuum is imparted, such as about 27 inches of mercury, a small amount of air is drawn through the membrane and passes through the wet clothes on its way to the vacuum pump 19. The air passing through the clothes under vacuum will displace the water held in the capillary crevices of the cloth, and will promote the movement of the water toward the vacuum drain. This action is primarily one of mechanical displacement and has a scavenging action. There is also a certain amount of vaporization promoted by the flow of air through the clothes.

The flexible membrane may be made of special sponge rubber or rubber-like material, or it may be a densely woven fabric, such as a nylon fabric chemically treated for this specific application.

As shown, the membrane 40 is corrugated, as by ring-like corrugations 49 and 50 molded in the membrane. The central portion 51 may be clamped between the cover 41 and a central plate 52 held by the bolt or rivet 53. The resiliency is such that normally it assumes the position shown in Fig. 1 when no vacuum is imparted within the tub; but it may move downwardly around the agitator 11 and press on the clothes when the vacuum is produced. When the cover 41 is lifted, the membrane 40 is also lifted, to provide access to the interior of the tub.

While the membrane is disclosed as being sufficiently flexible to press and squeeze the clothes, some of the advantages of my invention may be obtained by the use of a membrane which is not flexible to that degree.

In operation, the cover 41, and membrane 40 are lifted to open the machine. Soap, or other detergent, is placed in the cylindrical chamber 15 by lifting the cover 16, which is thereafter snapped back in place. Clothes are placed in the tub 10 around the agitator 11, and the cover 41 is then swung to the closed position of Fig. 1. The timer knob 29 is then moved from the off position to the start position. This rotates the switch cams on shaft 27, the cam 34 closing the switch 39 to start the timer motor 26. Simultaneously, or immediately thereafter, the cam 33 closes the switch 38 and maintains it closed for a sufficient length of time to cause the valve structure 23 to introduce the proper amount of water at correct temperatures into the tub 10. Continued rotation of the shaft 27 by the timer motor 26 then opens switch 38 and closes switches 35 and 36 for a sufficient length of time to produce the desired agitation by agitator 11. Thereafter switch 35 is opened and switch 37 is closed to cause operation of the pump 19 first to remove the main body of water and thereafter to impart a vacuum within the tub. The membrane 40 is forced down by the atmospheric pressure (air passing through openings 43) to squeeze the clothes, and when a sufficient vacuum is produced, atmospheric air passes through the membrane 40, and through the clothes and is continually discharged by pump 19. The foregoing cycle of operations may be automatically repeated one or more times by the timer, with the exception of the opening of the cover, and the introduction of soap or detergent. This produces one or more rinsing

operations. If desired, the last vacuum-producing operation may be longer than the previous ones, finally to dry the clothes to a greater degree than is necessary before rinsing operations.

In the modifications shown in Figs. 3, 4 and 5, the tub 110 is provided with an agitator 111, driven through the medium of shaft 112 and transmission 113 from motor 114.

The agitator may be of any type desired, and is here indicated as vertically reciprocable, being provided with a perforated soap chamber 115, having a removable cover 116. A flexible bellows 117, of rubber, rubber-like material, or metal, may be interposed between the agitator and tub, to provide a water seal at this point. The soap chamber 115 may be connected by passages 115a with the space beneath the agitator to provide drainage of the liquid from the chamber 115 and from the inner portion of the clothes while they are being pressed.

The transmission 113 may be any suitable transmission to impart the desired movement to the agitator 111. It may be provided with a solenoid control 118, which when energized drives (or stops, as desired) the agitator 111. The solenoid 118 may impart its control through the medium of a lever 118a or similar device.

The motor 114 may also drive the water and vacuum pump 119 through the medium of a transmission 120, indicated diagrammatically by a dotted line, which is controlled by a solenoid 121. Proper energization (or deenergization, as desired) of solenoid 121 causes motor 114 to drive the pump 119. The pump 119 has its intake connected to the tub 110 by the pipe 119a and has its discharge connected to a pipe or hose 119b which may discharge into a stationary tub or drain. The pipe 119a is provided with a solenoid valve 119c which is opened by proper energization (or deenergization) and vice versa.

A water supply pipe 122 may be provided with a combined solenoid, thermostatic and constant flow control valve structure 123, which is supplied by hot and cold water pipes 124 and 125. The construction of valve structure 123 is such that it supplies water of the desired temperature to the tub 110 at a constant rate of flow. Conveniently the pipe 122 discharges into the washing space through the medium of pipe 119a. The solenoid valve 119c is closed when the valve 123 is open, and vice versa.

The motor 114 and solenoid controls 118, 121, 123 and 119c may be controlled by a timer, for example as indicated in Fig. 5. The timer may include a timer motor 126 which drives the timer shaft 127 through the medium of speed reduction gearing or transmission 128. The shaft 127 may have a setting knob 129 and a plurality of disc cams 130 to 134 inclusive, which respectively actuate the switches 135 to 139 inclusive. These switches establish circuits from the power lines L and L₁ respectively through the motor 114, solenoid controls 118, 119c, 121 and 123 and timer motor 126.

While the foregoing washing machine structure has been described in some detail, it is to be understood that such structures may be varied, as desired.

Means are provided for removing the excess water, imparting a squeezing pressure on the clothes, imparting a vacuum around the clothes, and causing a flow of air through them. This

produces a very efficient wringing or drying action on the clothes.

To this end a porous, flexible membrane or diaphragm 140 is placed on the washing machine in such position as to impart a physical pressure upon the clothes to squeeze them when a vacuum is imparted within the machine. For example, a cover 141 may be hinged at 142 to the tub 110. The membrane 140 may be in the shape of a bag open at its upper and lower ends and have its upper periphery 144 secured to the periphery 145 of the opening 143 of the tub 110, which is opened and closed by the cover 141. The lower periphery 146, of the bag 140, is secured to the lower portion of the tub 110 at 147 in a manner to connect pipe 119a to the washing space within the bag.

Preferably the membrane 140 is of such porosity that at pressure differences less than one-half atmosphere the membrane will act as a water-tight and substantially air-tight membrane, particularly when wet, as it will be following a washing action. When a further vacuum is imparted, such as about 27 inches of mercury, a small amount of air is drawn through the membrane and passes through the wet clothes on its way to the vacuum pump 119. The air passing through the clothes under vacuum will displace the water held in the capillary crevices of the cloth, and will promote the movement of the water toward the vacuum drain. This action is primarily one of mechanical displacement and has a scavenging action. There is also a certain amount of vaporization promoted by the flow of air through the clothes.

The flexible membrane may be made of special sponge rubber or rubber-like material, or it may be a densely woven fabric, such as a nylon fabric chemically treated for this specific application.

While the membrane is disclosed as being sufficiently flexible to press and squeeze the clothes, some of the advantages of my invention may be obtained by the use of a membrane which is not flexible to that degree.

The tub 110 is perforated, as at 148 and 149 to allow air to enter into the space between the tub 110 and bag 140 at atmospheric pressure. A trough 150 with a drain 151 is provided to catch any water that might slowly filter through the bag 140.

In operation, the cover 141 is lifted to open the machine. Soap, or other detergent, is placed in the cylindrical chamber 115 by lifting the cover 116, which is thereafter snapped back in place. Clothes are placed in the tub 110 and bag 140 around the agitator 111, and the cover 141 is then swung to the closed position and latched, if desired, by a combined handle and latch 152. The timer knob 129 is then moved from the off position to the start position. This rotates the switch cams on shaft 127, the cam 134 closing the switch 139 to start the timer motor 126. Simultaneously, or immediately thereafter, the cam 133 closes the switch 138 and maintains it closed for a sufficient length of time to cause the valve structure 123 to introduce the proper amount of water at correct temperature into the tub 110. Continued rotation of the shaft 127 by the timer motor 126 then opens switch 138 and closes switches 135 and 136 for a sufficient length of time to produce the desired agitation by agitator 111. Thereafter switch 136 is opened and switch 137 is closed to energize solenoid 121 to cause operation of the

pump 119 and to energize valve 119c to open it, first to remove the main body of water and thereafter to impart a vacuum within the tub. The membrane 140 is forced inwardly toward agitator 111 by the atmospheric pressure (air passing through openings 148 and 149) to squeeze the clothes, and when a sufficient vacuum is produced, atmospheric air passes through the membrane 140, and through the clothes and is continually discharged by pump 119. The foregoing cycle of operations may be automatically repeated one or more times by the timer, with the exception of the opening of the cover, and the introduction of soap or detergent. This produces one or more rinsing operations. If desired, the last vacuum-producing operation may be longer than the previous ones, finally to dry the clothes to a greater degree than is necessary before rinsing operations.

While the form of embodiment of the invention as herein disclosed, constitutes a preferred form, it is to be understood that other forms might be adopted, as may come within the scope of the claims which follow.

What is claimed is as follows:

1. In a washing machine: a tub; means to create a vacuum within said tub; and a porous diaphragm for said tub having one side exposed to the atmosphere outside said tub and its other side exposed to the interior of said tub, the porosity of said diaphragm being of a character which is impervious to transmission of air when the pressure differential is below one-half atmosphere, and is pervious to the transmission of air when the pressure differential is above one-half atmosphere.

2. In a washing machine: a tub; means to create a vacuum within said tub; means to introduce liquid into said tub; and a porous diaphragm for said tub having one side exposed to the atmosphere outside said tub and its other side exposed to the interior of said tub, the porosity of said diaphragm being of a character which is impervious to transmission of air when the pressure differential is below one-half atmosphere, and is pervious to the transmission of air when the pressure differential is above one-half atmosphere.

3. In a washing machine: a tub; vacuum means to create a substantial vacuum within said tub; and a porous diaphragm for said tub having one side exposed to the atmosphere outside said tub and its other side exposed to the interior of said tub; the porosity of said diaphragm being of a character which is pervious to the transmission of air when a substantial vacuum is created in said tub.

4. In a washing machine: a tub; agitating means for said tub in the central lower portion of said tub; a cover for said tub; a porous diaphragm carried by said cover having one side exposed to the atmosphere outside said tub and its other side exposed to the interior of said tub, said diaphragm being in the form of a bag with its outer periphery and its center portion secured to said cover to form an annular bellows surrounding said agitator; and means to create a vacuum in said tub.

5. In a washing machine: a tub; agitating means for said tub; a cover for said tub; hinge means securing said cover to swing upwardly from said tub about said hinge means; a porous diaphragm carried by said cover having one side exposed to the atmosphere outside said tub and its other side exposed to the interior of said tub,

said diaphragm being in the form of a bag with its outer periphery and its center portion secured to said cover to form an annular bellows surrounding said agitator said diaphragm swinging upwardly with said cover; and means to create a vacuum to said tub.

RICHARD S. GAUGLER.
